CLAIM

The ornamental design for a dodo cute lamp, as shown and described.

DESCRIPTION

FIG. 1 is a top perspective view of a dodo cute lamp, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines showing in the drawings are included for the purpose of illustrating portions of the dodo cute lamp and forms no part of the claimed design.
